[57] CLAIM

The ornamental design for a prismatic cosmetic container, substantially as shown and described.

DESCRIPTION

FIG. 1 is a perspective view of the prismatic cosmetic container showing my new design;

FIG. 2 is a top view thereof;

FIG. 3 is a bottom view thereof;

FIG. 4 is a side view showing the two uppermost surfaces of the container shown in FIG. 1;

FIG. 5 is a side view wherein the cosmetic container has been rotated clockwise (as seen from the top) 90 degrees from the view in FIG. 4;

FIG. 6 is a view of the cosmetic container rotated clockwise (as seen from the top) 90 degrees from the view in FIG. 5;

FIG. 7 is a view of the cosmetic container rotated clockwise (as seen from the top) 90 degrees from the view in FIG. 6.

FIG. 1

FIG. 2
